(57) **CLAIM**

I claim the ornamental design for a combined pet litter container and tray, as shown and described.

DESCRIPTION

FIG. 1 is a perspective view of a combined pet litter container and tray showing my new design;

FIG. 2 is a perspective view thereof, illustrated with a portion of a lid removed;

FIG. 3 is an exploded perspective view of FIG. 1;

FIG. 4 is an exploded front elevational view of FIG. 1, the exploded rear elevational view being a mirror image thereof;

FIG. 5 is an exploded left-side elevational view of FIG. 1, the exploded right-side elevational view being a mirror image thereof;

FIG. 6 is an exploded top plan view of FIG. 1; and,

FIG. 7 is an exploded bottom plan view of FIG. 1.

The broken lines illustrate portions of the combined litter container and tray that form no part of the claimed design.
